(57) **CLAIM**

The ornamental design for a machine for preparing drinks, as shown and described.

DESCRIPTION

FIG. 1 is a top, front, right side perspective view of the machine for preparing drinks;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front, right side perspective view thereof with the tray in a closed position;

FIG. 9 is a front elevational view thereof with the tray in a closed position;

FIG. 10 is a back elevational view thereof with the tray in a closed position;

FIG. 11 is a right side elevational view thereof with the tray in a closed position;

FIG. 12 is a left side elevational view thereof with the tray in a closed position;

FIG. 13 is a top plan view thereof with the tray in a closed position, and,

FIG. 14 is a bottom plan view thereof with the tray in a closed position.

The broken lines that appear on the drawings form no part of the claimed design and are included for illustrative purposes only.
